UNITED STATES PATENT OFFICE.

ALONZO W. ALLEN, OF STREATOR, ILLINOIS, ASSIGNOR OF ONE-HALF TO CHARLIE E. GOLDSMITH, OF STREATOR, ILLINOIS.

PAPER-FOLDER.

1,286,487.

Specification of Letters Patent.

Patented Dec. 3, 1918.

Application filed June 17, 1918. Serial No. 240,378.

To all whom it may concern:

Be it known that I, ALONZO W. ALLEN, a citizen of the United States, residing at Streator, in the county of La Salle and State 5 of Illinois, have invented new and useful Improvements in Paper-Folders, of which the following is a specification.

My present invention pertains to a novel, and inexpensive article of stationery, and 10 it consists in the peculiar and practical paper folding device, hereinafter described and claimed, through the medium of which a cover for legal documents and other manuscripts may be correctly, neatly and conveniently folded.

In the accompanying drawings which are hereby made a part hereof:

Figure 1, is a front elevation, showing the arrangement of my novel folder to the paper 20 or cover, to be folded.

Fig. 2, is a section taken at a point slightly below the center line of my novel device and showing the position the paper or covers assumes in the device before the 25 bending operation takes place.

Fig. 3, is an end elevation illustrating the original position of the paper or cover and folder with respect to each other and further showing their relative position when 30 my novel device is put into operation as indicated by arrow.

Referring by numerals to said drawings: 1, is my novel device.

2, of Fig. 2, is the inner face of the device 35 against which the paper or cover rests in the operation of folding.

3, in Fig. 1, are the lips of the device between which the paper or cover is placed to be folded, the other lip of which, for an 40 important purpose, hereinafter set forth has a diagonally cut-off portion at 6.

4, is the paper or cover.

5, is the line on which the paper or cover 45 folds.

It will be gathered from the foregoing that my novel device, consists of a rectangular piece of stamped out sheet tin or such-

like bendable material, folded upon itself through its center, in the direction of its length: for the purpose of folding covers 50 for documents, such as are used for neatly holding papers in a packet, and where the occasion arises, for the more conveniently "backing" of legal documents. While the operation of folding covers for such purposes is in itself simple, by the use of my novel device the same may be accomplished evenly, quickly and neatly, without soiling the cover and avoiding unnecessary handling and consequent waste of paper. 55

The device is inexpensive to produce and consists of but one part, and may be embellished or ornamented so as to present an attractive appearance.

In the practical operation of the device, 60 the paper is placed into the receiving lips of the folder, made easy by reason of the diagonally cut off portion 6, and turned forward, when the paper will be creased at a point near its upper edge. 65

Although the drawings show the preferred embodiment of my invention, I would have it understood that such changes in the construction, as for instance, the handle and aperture for the suspending of the device in 70 a convenient place, may be made as fairly fall within the scope of my appended claim. 75

What I claim and desire to secure by Letters-Patent is:

As a new article of manufacture, the combination of a rectangular piece of sheet metal or other suitable material, bent at a point along its center in the direction of its length: and a finger portion and aperture arranged in one end of the folder, and a diagonally cut-out portion in the other end thereof. 80

In testimony whereof I have hereunto set my hand in presence of two subscribing witnesses.

ALONZO W. ALLEN.

Witnesses:

JOHN AUTOLIK,
W. C. GEIGER.
